FEEDING MECHANISMS FOR SEWING MACHINES

Nicholaus Knaus, Cranford, N. J., assignor to The Singer Manufacturing Company, Elizabeth, N. J., a corporation of New Jersey

Application June 30, 1950, Serial No. 171,325

6 Claims. (Cl. 112—209)

1

This invention relates to feeding mechanisms for sewing machines, and more particularly to that type of feeding mechanism known as a differential feed in which two work feeding elements are adapted to be actuated so as to exert unequal feeding actions on the work, thereby either to stretch or pull the work as required.

The invention has as a primary object to provide an improved differential feeding mechanism for sewing machines in which one of the two feeding elements may be dropped below the upper surface of the throat-plate when it is desired to discontinue the differential feeding action.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 represents an end elevation, partly in section, showing the feeding mechanism assembled in a partially illustrated overseaming machine.

Fig. 2 represents a sectional view taken substantially along the line 2—2 of Fig. 1.

Fig. 3 represents a sectional view taken substantially along the line 3—3 of Fig. 1.

Fig. 4 represents a fragmentary elevation view illustrating with solid lines the auxiliary feed-bar in its operative position and illustrating with dotted lines such feed-bar in its inoperative or throw-out position.

Fig. 5 represents a sectional view taken substantially along the line 5—5 of Fig. 1.

Fig. 6 represents a disassembled perspective view of the main and auxiliary feed-dogs and their actuating connection rods.

Fig. 7 represents a perspective view of the main and auxiliary feed-dogs both in their operative positions.

Referring now to the drawings, the reference numeral 10 denotes the frame or casing of an overseaming machine, 11 the head and 12 the needle plate (see Fig. 4) which is supported upon the frame in a conventional manner. The presser-foot 13 is supported on the head and the shank 14 of the foot is engaged by a compression spring 15 whereby the foot is normally pressed downwardly to confine the goods between the foot and the needle-plate 12. The rear portion of the shank 14 is mounted on a universal joint 16 in a conventional manner and a lever 17 is provided for relieving the pressure of the

spring 15. The machine is provided with a main rotary shaft 18 (see Fig. 2) which is journaled in the frame 10 and this shaft, through a link not herein illustrated, is connected with a needle carrier 19 pivoted in a bushing 20 so that the rotation of the shaft 18 effects the oscillation of the carrier within its bushing 20. The needle 21 is mounted in the carrier 19 and the oscillation of the latter causes the needle to reciprocate and penetrate the goods that is supported upon the needle-plate 12. Suitable stitch-forming implements or loopers cooperate with the needle to effect the formation of the overseaming stitches, but as these loopers and the manner of and the means for their actuation form no part of the present invention, their illustration and further description are not deemed necessary.

For a more complete description and illustration of a machine of the present type, reference may be had to my United States Patent No. 2,338,796, dated April 15, 1941.

The present work-feeding mechanism is of the differential type including a main feed-dog 22 and an auxiliary feed-dog 23 which are mounted, respectively, on the side-by-side main and auxiliary feed-bars 24 and 25 slidably supported at their forked rear ends 26 and 27 upon slide blocks 28 and 29. The feed-bars 24 and 25 receive their rising and falling movements from the feed-lift eccentric 30 on the main shaft 18; said eccentric being surrounded by the usual bearing block 31 which fits in ways 32 and 33 in the feed-bars 24 and 25. The feed and return movements are imparted to the feed-bars 24 and 25 from main and auxiliary feed eccentrics 34 and 35 removably and replaceably keyed upon the outer end of the main shaft 18 and held thereon by the nut 36. The main feed eccentric 34 is connected by a pitman 37 to the lateral post 38 rigid with the main feed-bar 24. The auxiliary feed eccentric 35 is connected by a pitman 39 to a lateral post 40 rigid with the auxiliary feed-bar 25. Alteration of the amplitude of the feed and return movements of the feed-dogs is effected by substitution of feed eccentrics of the desired eccentricities, for those of the machine. In other words, to change the length of the horizontal feed movements of either or both of the feed bars 24 and 25 it is necessary to remove one or both of the feed eccentrics 34 and 35 as the case may be, and substitute another or others of greater or less eccentricity. It is therefore necessary that each machine shall be supplied with a suitable set of eccentrics to produce the required different lengths of feed and degrees of gather-

3

ing or stretching. By means of the mechanism shown for giving the feed-dogs their four motion movements, it will be seen that each feed-dog 22 and 23 may be caused to operate independently of its companion.

The differential feed mechanism of the present machine differs from that disclosed in my above noted U. S. patent in that the forked rear end 21 of the auxiliary feed-bar 25, which carries the forward feed-dog 23, embraces a slide block 29 which is mounted upon an eccentric stud 41 carried by a horizontally disposed rock shaft 42 journaled in a bearing bracket 43 formed at the rear end of the machine frame. The rock shaft 42 is spring biased to a position in which the eccentric stud 41 is lowered (see Figs. 4 and 5), thereby depressing the rear end of the auxiliary feed-bar 25 and swinging the bar about the feed lift eccentric 30. This raises the forward end of the bar and the auxiliary forward feed-dog 23 carried thereby so that the auxiliary feed-dog is level with the main feed-dog 22. In this position the forward feed-dog has a greater effective feed stroke than the main feed-dog and causes fulling of the lower ply of the material.

An arm 44, secured to and projecting rearwardly from the rock shaft 42 is connected by a chain 45 to a suitable foot treadle, whereby the rock shaft 42 may be turned to cause the rear end of the auxiliary feed-bar 25 to be elevated and the forward end thereof to be lowered to drop the auxiliary feed-dog 23 below the upper surface of the throat-plate 12 sufficiently to render the auxiliary feed-dog ineffective, while still permitting it to be given its back and forth and up and down movements.

More specifically, the bearing bracket 43 is surrounded by a coil spring 46 one end 47 of which is biased against the frame member while its other end 48 is biased against the arm 44 so that the entire mechanism is normally thrown into its operative position as hereinabove described. Thus, whenever the chain 45 is moved downwardly, as by means of a foot treadle, the arm 44 turns its rock shaft 42 and thereby throws the eccentric 41 upwardly so as to drop the auxiliary or forward feed-dog 23 beneath the throatplate 12. The arm 44 is secured to its rock shaft 42 by means of a screw 49, and the upward movements of this arm are arrested by means of a depending finger 50 formed on the machine frame.

From the above, it is to be understood that the bearing block 31 forms a support having an axis common to both feed-bars 24 and 25, with reference to which axis the feed-dogs have pivotal and longitudinal movements. Furthermore, it is about this support axis that the auxiliary feed-bar 25 pivots whenever the operator depresses the chain 45 for the purpose of lowering the auxiliary feed-dog 23 to its inoperative position.

The main or primary feed-bar 24 is also forked as at 26 and this fork member embraces a slide block 28 which is mounted upon an eccentric stud 51 carried by a horizontally disposed rock shaft 52 which is journaled in a bearing 53 at the rear of the machine frame. Referring particularly to Fig. 5, it will be seen that the distal end of this rock shaft is provided with a screw slot 54. By inserting a screw driver into this slot 54 and turning the shaft 52 the elevation of the main feed-dog 22 may be adjusted to proper limits.

From the above it will be appreciated that the

4

present invention provides a simple but effective means for throwing one of the two feed-dogs out of effective operation during the running of the machine. Thus, whenever it is desired to discontinue the normal differential feeding action, it is only necessary to pull downwardly upon the chain 45 to effect a dropping of the auxiliary feed-dog 23 so that the latter will be effectively inoperative during the remaining portion of the sewing operation. By the same token, as soon as the operator wishes to render the auxiliary feed-dog operative so as to again effect a differential feeding action, it is only necessary to release the chain 45, whereupon the spring 46 will throw the arm 44 upwardly to pivot the auxiliary feed-bar 25 back into its operative position.

Having thus set forth the nature of the invention, what I claim herein is:

1. A sewing machine feeding mechanism comprising, a main feed-bar, an auxiliary feed-bar, a feed-dog carried upon one end portion of each of said feed-bars, means disposed intermediate the ends of said feed-bars for imparting lateral and differential longitudinal movements to said feed-bars, which lateral and differential longitudinal feed-bar movements constitute the work-feeding motions, normally stationary first and second means for respectively supporting the other end portions of each of said main and auxiliary feed-bars, and manually controlled means for causing relative lateral movement between said first and second supporting means thereby to render one of said feed-dogs inoperative.

2. In a sewing machine, two co-acting feeding mechanisms each including a feed-bar and a feed-dog carried by said feed-bar, the work-engaging surfaces of the two feed-dogs substantially defining a single horizontal plane, a rotary shaft disposed crosswise of said feed-bars, means on said shaft for imparting horizontal and vertical movements to each of said feed-bars, which horizontal and vertical feed-bar movements constitute the work-feeding motions, first and second members each slidably engaging and supporting one end portion of a respective one of said feed-bars, and manually controlled means for shifting one of said members vertically relative to the other thereby to pivot its associated feed-bar about said shaft so as to shift the feed-dog carried by the latter feed-bar out of said plane.

3. In a sewing machine having, two co-acting feeding mechanisms each including a feed-bar and a feed-dog carried upon one end of such feed-bar, a support forming a horizontal axis common to both feed-bars with reference to which axis the feed-dogs have pivotal and longitudinal movements, a shaft, and means on said shaft whereby vertical and differential horizontal longitudinal movements are imparted to said feed-dogs through the medium of said feed-bars; the invention which consists in the provision of means whereby one of said feed-dogs may be rendered inoperative, said last mentioned means comprising a pair of members each slidably engaging and supporting the other end portion of a respective one of said feed-bars, spring means for normally maintaining said pair of members positioned relative to each other so that the work-engaging surfaces of said feed-dog will substantially define a common horizontal plane, and manually controlled means for shifting one of said members vertically relative to the other

thereby to pivot one of said feed-bars about said axis so as to shift one of said feed-dogs out of said common horizontal plane.

4. In a sewing machine, a frame, two co-acting feeding mechanisms each including a feed-bar and a feed-dog carried upon one end of said feed-bar, a rotary element disposed intermediate the ends of said feed-bars and forming a horizontal axis common to both feed-bars with reference to which axis the feed-dogs have vertical pivotal and horizontal longitudinal movements, means connected with said rotary element whereby vertical and differential horizontal longitudinal movements are imparted to said feed-dogs through the medium of said feed-bars, first and second normally stationary means carried by said frame for respectively supporting the other end portion of each of said two feed-bars, and a manually controlled lever carried by said frame for causing vertical relative movement between said first and second means thereby to pivot one of said feed-dogs about said axis.

5. In a sewing machine, a frame, two co-acting feeding mechanisms each including a feed-bar and a feed-dog carried upon one end of said feed-bar, a rotary element disposed intermediate the ends of said feed-bars and forming a horizontal axis common to both feed-bars with reference to which axis the feed-dogs have vertical pivotal and horizontal longitudinal movements, means connected with said rotary element whereby vertical and differential horizontal longitudinal movements are imparted to said feed-dogs through the medium of said feed-bars, first and second normally stationary means including a rockable eccentric member carried by said frame for respectively supporting the other end portion of each of said two feed-bars, a manually controlled lever carried by said frame and connected

with said eccentric member for rocking the latter thereby to pivot one of said feed-dogs about said axis, and spring means engaging said frame and said lever for maintaining said lever in a predetermined position relative to said frame.

5 6. In a sewing machine, a frame, two co-acting feeding mechanisms each including a feed-bar and a feed-dog carried upon one end of said feed-bar, the other end portion of each feed-bar being 10 formed with a longitudinal slot, a rotary element disposed intermediate the ends of said feed-bars and forming a horizontal axis common to both feed-bars with reference to which axis the feed-dogs have vertical pivotal and horizontal longitudinal movements, means connected with said rotary element whereby vertical and differential horizontal longitudinal movements are imparted to said feed-dogs through the medium of said feed-bars, first and second normally coaxially arranged and stationary pins each disposed in a respective one of said feed-bar slots for supporting the slotted ends of said feed-bars, a manually controlled lever carried by said frame and connected with one of said pins for vertically adjusting such pin relative to the other pin thereby to pivot one of said feed-dogs about said axis, and spring means engaging said frame and said lever for maintaining said pins in a normally coaxial relationship.
